(57) CLAIM

I claim the ornamental design for a nameplate for cosmetic container, as shown and described.

DESCRIPTION

FIG. 1 is a front perspective view of the nameplate for cosmetic container showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view the nameplate for cosmetic container shown in an environment of use combined with a cosmetic container.

The broken lines in FIG. 8 show unclaimed environment only and form no part of the claimed design.

1 Claim, 6 Drawing Sheets
